UNITED STATES PATENT OFFICE.

SIMON S. SUTTON, OF ELDORADO, ILLINOIS.

STARTER FOR INTERNAL-COMBUSTION ENGINES.

1,111,683.

Specification of Letters Patent.

Patented Sept. 22, 1914.

Application filed January 7, 1914. Serial No. 810,818.

To all whom it may concern:

Be it known that I, SIMON S. SUTTON, a citizen of the United States, residing at Eldorado, in the county of Saline and State of Illinois, have invented new and useful Improvements in Starters for Internal-Combustion Engines, of which the following is a specification.

This invention relates to starters for internal combustion engines, the object in view being to provide simple, economical and reliable means whereby compressed air stored in a suitable tank by the operation of the engine itself is subsequently used in connection with a priming tube and properly arranged stop-cocks and a check valve controlled by-pass, to prime the combustion chamber of the engine cylinder with explosive mixture under the requisite compression to produce a full and powerful impulse on the piston when ignited by the usual spark device.

With the above and other objects in view, the invention consists in the novel construction, combination and arrangement of parts, as will hereinafter be more fully described, illustrated and claimed.

The accompanying drawing represents a side elevation showing the starting means of this invention applied to an internal combustion engine which is conventionally shown.

Referring to the drawing, A generally designates an internal combustion engine which is conventionally shown as comprising a cylinder B in which the usual piston reciprocates.

In carrying out the present invention I provide a priming tube 1 of any suitable length, one end of which is connected to the cylinder so as to discharge into the combustion chamber of said cylinder, the discharge end of said pipe being controlled by a stop-cock 2. At the opposite or filling end of the priming tube 1, I place a priming cup 3 having its own stop-cock 4. The stop-cocks 2 and 4 thus serve to close both ends of the priming tube 1.

5 designates a compressed air tank having a capacity equal to or greater than the combustion chamber of the cylinder so that a sufficient amount of air may be compressed in said tank to charge the combustion chamber of the engine with a pressure equal to the ordinary operating compression of said

engine. From the tank 5 an air pipe 6 leads to the priming tube 1 with which it communicates between the stop-cocks 2 and 4. A by-pass 7 connects the air tube 6 with the priming tube 1 and communicates with said priming tube between the stop-cocks 2 and 4. 60

The by-pass 7 is provided with a check valve 8 to prevent back pressure from the tank 5 reaching the priming tube 1 and combustion chamber of the engine. A stop-cock 9 is arranged in the air pipe 6 between the priming tube 1 and the junction of the air tube 6 and by-pass 7. Another stop-cock 10 is arranged in the air pipe 6 between the compressed air tank 5 and the junction of the 70 air pipe and by-pass 7.

The operation of the starting means hereinabove described is as follows. When the engine is to be stopped, the fuel supply is first cut off thereby terminating the explosions and preventing any further admission 75 of gas to the cylinder. At the same time, the stop-cocks 2 and 10 are opened and while the engine is still turning over, the piston acts as an air compressor forcing air past 80 the check valve 8 into the tank 5. In order to prevent any possible leakage of the compressed air in the tank 5, the stop-cock 10 may then be closed.

When it is desired to start the engine, a 85 suitable amount of gasoline or other liquid fuel is introduced through the priming cup 3 into the priming tube 1 and the stop-cock 4 closed, thus trapping said fuel in the priming tube. The stop-cocks 9 and 10 are then 90 opened so that the compressed air is delivered into the priming tube 1 behind the liquid fuel contained therein. The stop-cock 2 is then opened and the fuel is forced quickly by the compressed air into the combustion chamber. Thus an explosive mixture under full engine compression is admitted into the combustion chamber and the piston being set just over or past the center, the stop-cock 2 is then closed and the compressed charge of gas is ignited by the usual 95 ignition device which may, if desired, be tripped by hand or by turning over the wheel of the engine. Thereupon a full impulse is given to the piston and while the 100 engine is turning over, the ordinary fuel supply may be opened whereupon the engine 105 will take up its own cycle of operation.

If desired, a spray tube 11 may be placed at the discharge end of the priming tube 1 110

and within the combustion chamber so as to atomize and thoroughly distribute the explosive mixture throughout the combustion chamber, said tube being shown as formed 5 with a large number of perforations 12 through which the explosive mixture is expelled.

What I claim is:

1. A starter for internal combustion engines, comprising a priming tube arranged 10 to discharge into the combustion chamber of the engine, a priming cup on the filling end of said tube provided with a stop-cock, a stop-cock controlling the discharge end of 15 said tube, a compressed air tank, an air pipe leading from said tank into said priming tube between the priming cup cock and the discharge end cock, a by-pass leading from said air pipe into said priming tube between 20 the priming cup cock and discharge end cock, a check valve in said by-pass, and a stop-cock controlling said air pipe and located between the priming tube and the junction of the air pipe and by-pass.

2. A starter for internal combustion engines, comprising a priming tube arranged 25 to discharge into the combustion chamber of the engine, a priming cup on the filling end of said tube provided with a stop-cock, a stop-cock controlling the discharge end of 30 said tube, a compressed air tank, an air pipe leading from said tank into said priming tube between the priming cup cock and the discharge end cock, a by-pass leading from 35 said air pipe into said priming tube between the priming cup cock and discharge end cock, a check valve in said by-pass, a stop-cock controlling said air pipe and located between the priming tube and the junction of the air pipe and by-pass.

In testimony whereof I affix my signature in presence of two witnesses.

SIMON S. SUTTON.
